DOVETAIL CONSTRUCTION

Burnie J. Craig, Los Angeles County, Calif.

Application April 30, 1949, Serial No. 90,597

4 Claims. (Cl. 292—341.12)

1

This invention relates to a dovetail construction.

The general object of the invention is to provide an improved dovetail construction particularly adapted for use on automotive vehicles.

A further object of the invention is to provide a dovetail construction including novel means for mounting the dovetail member.

Other objects and the advantages of the invention will be apparent from the following description taken in connection with the accompanying drawings, wherein:

Fig. 1 is a plan view of the latch housing blank;

Fig. 2 is a view of the latch housing in completed form;

Fig. 3 is a section taken on line 3—3, Fig. 2;

Fig. 4 is a plan view of the blank for the catch release arm support;

Fig. 5 is a top view of the catch release arm support after the blank shown in Fig. 4 is folded;

Fig. 6 is a front view of the catch release arm support;

Fig. 7 is an edge view of the catch release arm support;

Fig. 8 is a rear view of the catch release arm support;

Fig. 9 is a bottom view of the catch release arm support;

Fig. 10 is a view similar to Fig. 8, showing the dovetail member in fitted position;

Fig. 11 is a sectional view with the front portion removed, showing the bolt striking the catch and depressing the latter;

Fig. 12 is an extended view showing the elements of the dovetail member;

Fig. 13 is a side elevation of the dovetail member in assembled form;

Fig. 14 is a bottom view of the dovetail member, and

Fig. 15 is an isometric view showing the release arm.

The subject matter described and claimed in this application was disclosed in my prior application Serial No. 533,958, filed May 3, 1944, now Patent No. 2,450,372, granted September 28, 1948.

In the accompanying drawings the construction which includes the dovetail is shown as embodied in a catch device indicated generally at 168 (Fig. 11). As shown, the catch device includes a catch housing, indicated generally at 170 and which is pivoted to the catch support housing, and a support which is indicated generally at 171 and is arranged in the catch support

2

housing and which serves to support a catch release arm. The catch or projection casing 170 has a catch 203 mounted thereon. The catch 203 is engaged by a bolt 30 mounted in a vehicle door. The detailed construction of the catch and bolt and related parts form no part of the present invention, being shown and described in the applicant's Patent No. 2,450,372, granted September 28, 1948.

10 The catch housing 169 (see Figs. 1 and 2) is preferably made from a blank which includes a rectangular body portion 172 having bent up end flanges 173 and 173a and having an edge flange 174. The body 172 includes an upper jaw portion 172a which is spaced from a lower jaw portion 172b, the two jaw portions being rigidly connected in a unitary manner by a vertical portion 172c to provide a generally C-shaped body. Opposite the flange 174 the body 172 has upper and lower edge flanges 175 and 175a which are separated, when the blank is bent to completed form, by a tapering slot 176.

15 At the lower side of the slot 176 a flange or guiding part 177 is bent up at right angles to the body and this flange 177 is provided with a rectangular slot 178 through which the catch 203 projects. From the flange 177 a second flange 179 extends and is bent at right angles to the flange 177 as shown in Fig. 3. Opposite to the flange 177 a short flange 179a is bent up perpendicular to the body 172.

20 The body at the inner end of the slot 176 is shown as reinforced by a strip of metal 179b which may be spot welded in place. This layer of metal 179b as well as the portion of the body 172 adjacent thereto is provided with spaced upper and lower slots 179c and 179d into which ears, not shown, on the bolt project when they are moved to catch releasing position. The meeting edges of the housing flanges may be suitably secured together by welding if desired or the entire catch support housing may be made as a die casting or in any other suitable manner.

25 The support 171 for the catch release arm is made from a blank 210 shown in Fig. 4 as including a front portion 211 and a rear portion 212 and an end 213. The blank includes aligned apertures 214 and 215 while the front includes another aperture 216 and the back another aperture 217. The front has punched out tongues 218 and 219. The back further includes a tongue 220 which has a wing 221 on the end thereof.

30 The blank is bent into the form shown in Figs. 5 to 9 inclusive, with the tongues 218 and 219 extending perpendicular to the back. The

tongue 220 has small end tongues 223 and 224 thereon which are arranged in the slots from which the tongues 218 and 219 are bent. The wing 221 is bent at substantially right angles to the tongue 220.

The front is provided with an aperture 225 and with an elongated slot 226, the latter extending from the upper edge of the front. The front is cut away as at 227 for a purpose to be presently described. The front of the support 171 is provided with a bolt receiving slot 228, the edges of which converge towards a rear edge 230.

A dovetail wedge member is indicated at 231 (see Figs. 12 to 15). This dovetail may be made as a die casting or otherwise although it is shown in the accompanying drawing as made from three blanks of sheet material, 232, 233 and 234. The blank 232 has a closed slot 234' therein and has an open ended slot 235 spaced inwardly from the slot 234'. The blank 233 has an open ended slot 236 which is aligned with, and larger than, the slot 235. The blank 234 has a slot 234''. The layers 232, 233 and 234 are superimposed and are secured together as by spot welding.

The dovetail includes a face 237, Fig. 10, which engages the flange 220 on the support 171 and has a face 238 which is adapted to be engaged by the bolt or abutment 30 carried by a door when the latter moves into closed or engaged position. The tongues 218 and 219 on the support 171 fit in the slot 235 and 234', respectively, on the dovetail and serve to hold the dovetail in assembled position and to guide the dovetail in its sliding movement parallel to the flange 220. To permit the sliding action the slot 234'' is longer than the tongue 219 which fits in it. One side of the dovetail slidably engages the face of the portion 211 adjacent to the tongue 219, while the other side of the dovetail is engaged by the portion of the body 172 which is adjacent to the flange 179a.

The slot 236 receives a spring 239 which engages an upwardly directed end portion 240 on the tongue 218 and serves to normally urge the dovetail outwardly to the position shown in Fig. 10. When the bolt 30 strikes the dovetail (see Fig. 11) it slides the dovetail along the flange 220 which latter slants outwardly and whenever any loose play occurs the spring 239 pushes the dovetail back into tightly wedged engagement with the bolt. The dovetail is limited in its forward movement by the flange tongue or stop portion 221 and in its rearward movement by engagement of the end of the slot 234' with the tongue 219.

Having thus described my invention, I claim:

1. A laminated dovetail comprising a series of superimposed layers of sheet material, each of said layers having parallel planar faces, an intermediate layer of the series having a portion between the edges thereof removed to form an open ended slot with the open end disposed at one end of the dovetail, a second layer of the series engaging one face of the intermediate layer and including a portion overlapping the open ended slot to close one side of the latter, a third layer of the series engaging the other face of the intermediate layer and including a portion overlapping the open ended slot to close another side of the latter, the second mentioned layer including an elongated slot closed at both ends, the said intermediate layer including a portion overlapping the last mentioned slot to close one side of the latter, the last mentioned slot being open outwardly and adapted to slidably receive a guide

member on a support, all of the layers of the dovetail at one edge having a continuous coplanar engaging face adapted to slidably engage a support, all of the layers of the dovetail at the edge opposite to the said engaging face having a second continuous engaging face adapted to engage a door abutment, and means to hold all of the layers together.

2. A keeper structure adapted to be fastened to a vehicle for cooperative engagement with door abutment means carried on a swinging door, comprising a unitary, generally C-shaped body having a front face and having upper and lower opposed jaw portions which are integral continuations of the front face, said jaw portions being spaced apart vertically to provide an opening closed at its inner side by a vertical portion of the keeper body and including a part which is an integral continuation of the front face and is disposed substantially perpendicular to the front face and which rigidly connects the upper and lower spaced jaw portions, a dovetail wedge, means including a portion on one of the jaw portions and having a surface slidably engaged by a face of the dovetail wedge for slidably mounting the dovetail wedge for movement on said one of the jaw portions, and spring means urging the dovetail wedge outwardly, the other jaw portion of the keeper body having a surface disposed on a part thereof which is a continuation of the front face of the body and is disposed perpendicular to the front face of the body and from which a projection extends for cooperation with the door abutment means, the door abutment means being movable between the other jaw portion and the dovetail wedge in wedging relation thereto, the upper and lower jaw surfaces being held by the keeper body in fixed vertically spaced relation.

3. A keeper structure adapted to be fastened to a vehicle for cooperative engagement with door abutment means carried on a swinging door, comprising a unitary, generally C-shaped body having a front face and having upper and lower opposed jaw portions which are integral continuations of the front face, said jaw portions being spaced apart vertically to provide an opening closed at its inner side by a vertical portion of the keeper body and including a part which is an integral continuation of the front face and is disposed substantially perpendicular to the front face and which rigidly connects the upper and lower spaced jaw portions, a dove-tail wedge, means including a portion on one of the jaw portions and having a surface slidably engaged by a face of the dove-tail wedge for slidably mounting the dovetail wedge for movement on said one of the jaw portions, and spring means urging the dovetail wedge outwardly, the other jaw portion of the keeper body having a surface disposed on a part thereof which is a continuation of the front face of the body and is disposed perpendicular to the front face of the body and from which a projection extends for cooperation with the door abutment means, the door abutment means being movable between the other jaw portion and the dovetail wedge in wedging relation thereto, the upper and lower jaw surfaces being held by the keeper body, in fixed vertically spaced relation, the said jaw portion which is opposite to the dovetail wedge including a guiding part which is an integral continuation of the front face and which is sloped downwardly and projects in advance of the dove-tail wedge so that the door abutment means will

engage and slide along such guiding part before the door abutment means engages the dovetail.

4. A keeper structure adapted to be fastened to a vehicle for cooperative engagement with door abutment means carried on a swinging door, comprising a unitary, generally C-shaped body having a front face and having upper and lower opposed jaw portions which are integral continuations of the front face, said jaw portions being spaced apart vertically to provide an opening closed at its inner side by a vertical portion of the keeper body and including a part which is an integral continuation of the front face and is disposed substantially perpendicular to the front face and which rigidly connects the upper and lower spaced jaw portions, a dovetail wedge, means including a portion on one of the jaw portions which has a surface slidably engaged by a face of the dovetail wedge for slidably mounting the dovetail wedge for movement on said one of the jaw portions, and spring means urging the dovetail wedge outwardly, the other jaw portion of the keeper body having a surface disposed on a part thereof which is a continuation of the front face of the body and is disposed perpendicular to the front face of the body and from which a projection extends for cooperation with the door abutment means, the door abutment means being movable between the other jaw portion and the dovetail wedge in wedging relation thereto, the upper and lower

15

20

25

30

jaw surfaces being held by the keeper body in fixed vertically spaced relation, the said jaw portion which is opposite to the dovetail wedge including a guiding part which is an integral continuation of the front face and which is sloped downwardly and projects in advance of the dovetail wedge so that the door abutment means will engage and slide along such guiding part before the door abutment means engages the dovetail, the said one jaw portion at its outer end including a stop portion which is an integral continuation of the front face portion of the body and between which and the vertical portion of the keeper body the said dovetail wedge is slidably.
